(57) CLAIM

The ornamental design for a personal towel holder, as shown and described.

DESCRIPTION

FIG. 1 is a top front perspective view of a personal towel holder;

FIG. 2 is a front elevation view thereof;

FIG. 3 is a rear elevation view thereof;

FIG. 4 is a left side elevation view thereof; the right side view being a mirror image thereof;

FIG. 5 is a top elevation view thereof; and,

FIG. 6 is a bottom elevation view thereof.

The broken lines shown represent unclaimed subject matter and form no part of the claimed design.
